John W. Dyer

Inventor

UNITED STATES PATENT OFFICE.

MICHAEL WILSON, OF BROOKLYN, NEW YORK.

WINDOW GUARD.

Application filed January 15, 1921. Serial No. 437,375.

To all whom it may concern:

Be it known that I, MICHAEL WILSON, a citizen of the United States, and resident of the borough of Brooklyn, county of Kings, city and State of New York, have invented 5 certain new and useful Improvements in Window Guards.

This invention relates to improvements in window guards and has for its principal object to provide a device which may be readily attached to a window so that when the window is open the passage is barred, thereby preventing the entrance of sneak-thieves and other unauthorized persons.

Another object of the present invention is 15 to provide a device which will effectively prevent children from falling out of an open window.

A further object of the invention is to provide a guard which may be readily released 20 from the interior so that in case of fire escape through the window may be made.

With these and other objects in view the invention consists of a novel construction, 25 combination and arrangement of parts which will be fully set forth in the following specification, claimed and illustrated in the accompanying drawings in which:—

Fig. 1, is a face view of the window illustrating this guard attached thereto showing portions of the sash broken away to more clearly illustrate the details of construction.

Fig. 2, is a vertical sectional view through Fig. 1.

Fig. 3, is a sectional view through one of the securing elements by which the guard is held in place and

Fig. 4, is a fragmentary view partly in section of the upper sash illustrating the 40 locking means therefor.

Referring to the drawings in detail the numeral 5 designates the wall of the building in which the window is mounted and this wall 5 is provided with a pocket 6 as is customary 45 in frame buildings having relatively thick walls.

The window frame 7 is mounted in the window opening in the wall and is provided with the upper and lower sashes 8 and 9 respectively. The bottom rail 10 of the lower sash is provided on its under side with a longitudinal groove for the reception of the upper bar of the guard, while the side rails of the lower sash are provided with longitudinal bores 11 through which the supporting rods of the guard extend.

The guard is designated in its entirety by the numeral 12 and comprises the upper bar 13 and lower bar 14 which are connected by vertical fillers 15 which are adapted to slide 60 through openings 16 in the sill 17. Vertically extending supporting bars 18 are secured adjacent opposite ends of the bar 13 in alignment with the bores 11 and said supporting bars are slightly longer than the side rails 65 of the sash 9 and have their upper ends provided with screw threads upon which suitable securing nuts may be threaded.

While it is obvious that any suitable nut may be used in connection with the threaded 70 ends of the bars 18, it has been found preferable to use a nut which may be rapidly released so that in case of fire the window may be opened without raising the guard. To this end a nut such as illustrated in Fig. 3 75 has been designed which comprises a hollow substantially spherical body 19 provided with a bore 20 for the reception of the shank 21 of a press button 22. A slightly enlarged bore 23 extends into the body 19 in alignment 80 with the bore 20 and forms a seat for the inner end of a compression coil spring 24, the outer end of which engages the outer side of the button 22.

Pivotedly mounted on a suitable shaft 25 85 extending horizontally through the hollow body 19 are jaws 26, the inner faces of which are threaded to match the thread on the upper ends of the rods 18 and these jaws are provided with extensions 27 which are 90 adapted to be engaged by the inclined faces 28 of the inner end of the shank 21. It will be obvious that upon applying pressure to the button 22, the inclined faces 28 will engage the arms 27 and thereby cause the jaws 95 26 to move outwardly so that the threads on the inner faces thereof will disengage the threads on the upper ends of the bars 18. In this way it will be evident that the guard may be released so that the window is left 100 free to open without moving the guard and thereby allowing for the escape of the occupants of the building in case of fire.

In order to hold the upper sash against movement when the lower sash is raised, a 105 suitable locking bolt 29 is slidably mounted in a bore 30 in one of the side rails of the upper sash.

While in the foregoing there has been shown and described a preferred embodiment of this invention, it is to be understood 110 that certain minor changes in the details of

construction, combination and arrangement of parts may be resorted to without departing from the spirit and scope of the invention as claimed.

5 What is claimed is:—

1. The combination with a window having a sliding sash, said sash having a groove in the outer face of one of its rails and provided with bores in the rails extending at right angles to the grooved rail, of a guard having its upper end seated in the groove in said rail, supporting rods extending through the bores and having certain of their ends connected to the guard and means to removably secure the rods in the bores.

2. The combination with a window having a vertically sliding sash provided in its bottom rail with a groove and having bores extending through the parallel side rails, of a guard comprising an upper bar and a lower bar, vertically extending bars connecting the upper and lower bars, said vertically extending bars being slidable through openings in the window sill, supporting bars extending through the bores and being connected at their lower ends to the upper bar of the guard and means connected to the upper ends of the supporting bars to removably secure said supporting bars in the bores.

MICHAEL WILSON.
